UNITED STATES PATENT OFFICE.

MORRIS W. POOL, OF NEW YORK, N. Y., ASSIGNOR TO UNION TYPEWRITER COMPANY, OF JERSEY CITY, NEW JERSEY, A CORPORATION OF NEW JERSEY.

TYPE-WRITING MACHINE.

No. 899,616.

Specification of Letters Patent. Patented Sept. 29, 1908.

Application filed October 16, 1905. Serial No. 283,016.

To all whom it may concern:

Be it known that I, MORRIS W. POOL, citizen of the United States, and resident of the borough of Brooklyn, city of New York, in the county of Kings and State of New York, have invented certain new and useful Improvements in Type-Writing Machines, of which the following is a specification:

My invention relates to the tabulating mechanism of typewriting machines and particularly to that class of tabulating mechanisms which comprise a denomination stop member and a plurality of coöperating column stops.

The main object of my invention is to provide improved means to cause a denomination stop member and any selected column stop to be positioned at a single operation to coöperate with each other so that when such coöperation is brought about any selected denomination position in any selected column will be brought to the printing point.

To the above and other ends, my invention consists in the features of construction, combinations of devices and arrangements of parts hereinafter described and particularly pointed out in the claims.

My invention is shown as applied to the machine known as the No. 6 Remington typewriter, a plurality of adjustable column stops being shown mounted on the carriage of the machine and a single denomination stop member also being shown, which member is variably movable by a plurality of keys to bring it to a position where it may coöperate with any selected one of the plurality of column stops at any selected denominational position in the column to which said selected column stop relates. It is to be understood, however, that my invention may be applied to other styles of writing machines and other forms of tabulating devices besides those illustrated.

In the accompanying drawings, Figure 1 is a top plan view of a typewriting machine and tabulating mechanism embodying my invention, various parts being omitted and other parts being broken away. Fig. 2 is a central, longitudinal, sectional view of the machine and the associated tabulating devices, parts of the machine being omitted. Fig. 3 is a fragmentary top plan view showing the guide comb for the denomination stop member. Fig. 4 is an enlarged fragmentary perspective view showing the lower portion

of the denomination stop member, as well as the bearing of said member, one of the actuating keys and the carriage releasing bar. Fig. 5 is an enlarged side view, partly in section, of one of the actuating keys, said view also showing the release bar or plate in section. Fig. 6 is a view corresponding to Fig. 5 but showing the key in a different position. Fig. 7 is a front, sectional view of the key shown in Fig. 5.

Referring more especially to Figs. 1 and 2, 1 indicates the base of the machine supporting corner posts 2 which latter sustain a top plate 3. A series of type bar hangers are circularly arranged on the top plate, each hanger 4 pivotally supporting a type bar 5 which is connected by a link 6 with a printing key lever 7 fulcrumed at 8 in the rear of the base and provided with a restoring spring 9. The type bars are adapted to coöperate with the under side of a paper support or platen 10 mounted in a platen carrier 11, which, in turn, is pivotally connected by links 12 with a carriage truck 13. The platen carriage comprises the carrier 11 and truck 13 and is provided with rollers 14 and 15 which coöperate respectively with the front and back guide rails 16 and 17 respectively to support and guide the carriage as it is moved from side to side of the machine. A feed rack 18 is secured to arms 19 pivoted at 20 in the carriage truck, and said feed rack normally meshes with a feed pinion 21 fixed to the front end of a shaft 22 which has its bearings in a bracket 23 secured to the top plate by screws 24. An escapement wheel 25 is mounted on the rear end of the shaft 22, and adapted to coöperate with said escapement wheel are feed dogs 26 mounted at the top of a dog rocker 27 pivoted to a fixed part of the machine. Secured to the dog rocker are forwardly extending arms 28 which are connected by hook-like members 29 with a universal bar 30 which extends from side to side of the machine beneath the series of key levers 7. When any key lever is actuated to operate the printing mechanism, the universal bar is thereby actuated, causing the dogs 26 to coöperate in a known manner with the escapement wheel 25 to permit the carriage to be drawn a letter space distance in printing direction under the influence of a spring drum 31 with which the carriage is connected by a band 32.

A rack bar 33 extends parallel with the car-

riage truck and is adjustably secured by screws 34 to the rear ends of arms 35 extending rearwardly from brackets 36 which are bifurcated to fit over or embrace the carriage truck 13 and are removably and adjustably secured thereto by screws 37. The front and rear faces of the rack bar 33 are formed with grooves or notches 33^a a letter space distance apart and the top of the rack bar is preferably provided with a scale corresponding to the ordinary carriage and platen scales of the machine. The rack 33 is adapted to receive one or more column stops, four of such stops being shown in the drawings and marked respectively 38, 39, 40 and 41. Each of the column stops may be formed of a flat piece of metal cut away to embrace the rack bar 33 and to fit into the notches 33^a of said rack bar. The column stops generally resemble each other in construction but differ in respect to the extent to which they extend rearwardly from the rack bar or support 33. As will be noted from an inspection of Figs. 1 and 2, the stops from left to right extend rearwardly progressively increasing distances, or, in other words, they comprise a series of stepped stops, the stop 38 having its contact portion extending rearwardly to a less extent than the stop 39, which, in turn, extends rearwardly to a less extent or degree than the stop 40, the said stop 40 extending rearwardly to a less extent than the stop 41. Each stop determines a columnar field, and the number of columnar fields depends on the number of column stops which may, of course, vary with the work in hand.

A right angled bracket 42 is secured to the top 1^a of the rear of the base by headed screws 43. The bracket 42 is perforated near its top to receive a bearing member 44 (Fig. 4) for the denomination stop member, said bearing member comprising a cylindrical body portion 45 from which project rearwardly ears 46. The front face of the base portion 45 contacts with the rear face of the bracket 42 and projecting forwardly from the portion 45, through the bracket 42, is a cylindrical pivot portion 47, said pivot portion being shouldered away and threaded as indicated at 48. A securing nut 49 and a locking nut 50 are screwed on the threaded portion 48, the nut 49 being screwed up until it abuts against the shoulder formed on the part 47, in which position said securing nut 49 is in easy contact with the front face of the bracket 42 but so that the pivotal portion 47 of the member 44 may turn readily in the bracket 42. The ears 46 are perforated to receive a short shaft 51 which serves as a fulcrum for a denomination stop member which includes a lever 52. The lever 52 extends upwardly and leftwardly from its fulcrum 51 and is formed at its top with a forwardly curved portion 52^a which is adapted to coöperate with the column stops. A lug

52^b (Fig. 2) depends downwardly from the lower edge of the contact portion 52^a of the stop member 52 and said lug 52^b is adapted to enter the spaces between teeth 53 in a guide comb 54 (Fig. 3), the front portion 70 whereof is formed with a groove 55 (Fig. 2) which receives the downwardly extending lip 3^a of the top plate, said guide comb being secured in place by screws 56. The lever 52 may swing about the pivot 47 to bring the lug 52^b opposite any one of the notches between the teeth 53, which teeth are a letter space distance apart, and said lever may swing about the pivot 51 to cause said lug to enter one of said notches. When the lug 52^b 80 is thus engaged with the guide comb, the associated lever 52 is firmly held from lateral movement and consequently is not disturbed by the coöperating column stop when the latter contacts with the part 52^a as presently 85 to be described. The guide comb 54 is best shown in Figs. 2 and 3, and is omitted from Fig. 1 for the sake of clearness.

The means for setting the lever 52 coöperate with the lower arm of said lever, which 90 extends downwardly and rightwardly from the fulcrum 51 and has its end perforated to receive rivets 57 which pass through ears 58 extending upwardly from a horizontally disposed cross bar 59 (Figs. 2 and 4). The ears 95 58 are formed about midway of the length of the cross bar 59 and are arranged far enough apart to permit the lower end of the lever 52 to fit snugly between them, so that when the rivets 57 are secured in place the lever 52 100 and cross bar 59 form practically a single denomination stop member somewhat like an inverted T in shape. The bar 59 is provided with a plurality of pins or studs 60 which project from its under surface, eight 105 of such pins being shown in the drawings. A spring member 61 is secured by screws 62 to the bearing member 44 between the ears 46. The spring member 61 is bifurcated and the arms 63 of the bifurcated portion are curled 110 at their lower ends, as indicated at 63^a (Fig. 4), to serve as bearings for a small wheel or roller 64 which constantly engages the rear edge of the lower arm of the lever 52 and tends to turn said lever about the fulcrum 51 115 and press it against a fixed abutment 65 projecting from the rear of the base of the machine (Fig. 2). As shown in Fig. 2, a coiled spring 66 encircles the body portion 45 of the member 44, one end of said spring engaging 120 with the upper arm of the lever 52 and the other end being secured in the bracket 42. The spring 66 tends constantly to swing the upper arm of the lever 52 leftward about the fulcrum 47 and the lower arm of said lever 125 rightward about said fulcrum, said spring serving normally to maintain the right end of the bar 59 in contact with a stop member 67 suitably secured to the base of the machine and to maintain the denomination stop mem- 130

ber, comprising the lever 52 and the bar 59, in the position indicated in Fig. 1.

A plurality of tabulator push rods 68 are disposed fore and aft of the machine beneath the base, eight of such rods being shown in the drawings. A bearing bar 69 is secured to the sides of the base by screws 70 and is provided with a series of openings through which the rods 68 pass, the bar 69 serving as a bearing for said rods, which, forward of the bar 69, fan outwardly as they approach the front of the machine. Each push rod 68 is provided with a feather 68^a which co-operates with a groove in the bar 69 and prevents any rotary movement of the rod 68. A restoring spring 71 has one end secured to a hook 72 on the bar 69 and the other end secured to a collar 73 fixed to the rod 68 by a screw 74, and said spring 71 serves normally to maintain a pin 68^b on the rod 68 in contact with the rear face of the bar 69, thereby limiting the forward longitudinal movement of the rod 68.

The rear end of each rod 68 has secured to it, by means of a set screw 75, a positioning 25 and cam member 76, each of said members 76 comprising a cylindrical portion 77 (Fig. 4) which is formed with a hole which fits over the rear end of the associate rod 68, and also comprising a cam face 78 and a retaining recess 79. The cam face and recess of each of the members 76 are adapted to co-operate with one of the pins 60, depending from the bar 59. It will be noted from an inspection of Fig. 1 that in shape each member 76 differs 35 from its neighbors, the cam faces from right to left becoming progressively more and more acute, the extreme left-hand member 76 having no cam face but having only the retaining recess 79.

40 The forward end of each rod 68 terminates in a spherical portion 80 (Figs. 5 and 6) and the said spherical end serves as a bearing for a tabulating key 81. Each key 81 comprises a body portion 82, the front face whereof is rounded and from the rear face whereof projects a lug 83 which is recessed to receive the spherical end 80 of the associate push rod. Retaining plates 84 and 85 are secured to the rear face of the lug 83 by screws 86 and serve 45 to retain the key 81 in place on the spherical portion 80 of the push rod. It will be observed that by this construction a ball and socket joint is provided which permits of free movement of the key 81 in any direction. 50 The rounded front face of the body portion 82 of each key is formed with a plurality of recesses or depressions, four of such depressions being shown in the drawings and numbered 87, 88, 89 and 90. The depressions 87 to 90 are respectively stamped or marked 55 with the numerals "1", "2", "3" and "4". Projecting rearwardly from the body portion 82 are limiting pins 91, 92, 93 and 94. The pin 91, which is the shortest of the four, 60 is directly behind the depression 87 in the

front face of the key; the pin 92, which is somewhat longer than the pin 91, is behind the depression 88; the pin 93, which is in turn somewhat longer than the pin 92, is behind the depression 89; and the pin 94, which is the longest, is behind the depression 90. A four-armed positioning device 95 is secured to each rod 68 by a screw 69 in such a position that each of the limiting pins on the key is confined between two arms 97 of said positioning device 95, the arrangement being best understood from a consideration of Figs. 4 and 7 of the drawings.

The rear portions of the limiting pins are curved outwardly and the ends are beveled so that they may properly co-operate with a 80 sliding release plate or bar 98, which, as best appears in Fig. 1, extends from side to side of the machine just back of the front of the base. Near its ends the release plate 98 is provided 85 with short rearwardly extending bearing rods 99 which are received in bearing brackets 100, the latter being secured to the sides of the base by securing screws 101, so that the plate has a limited sliding movement fore and 90 aft of the machine. Secured to the back of the release plate at about its center is a rearwardly extending rod 102, the rear end of said rod 102 being pivotally connected at 103 with the downwardly extending arm 104 of a 95 bell crank lever 105 which is pivoted at 106 to a lug 107 depending from about the middle of a bar 108 which extends from side to side of the machine and is secured to the top of the base. The rearwardly projecting arm 100 109 of the bell crank lever 105 is pivotally connected at 110 with an upwardly extending link 111 which passes through a hole in the top plate and is pivotally connected at 112 with a rack-lifting member 113. The 105 member 113 is pivoted at 114 to the escape- 110 ment bracket 23 and extends forwardly beneath and to a short distance in front of the feed rack 18, its forward end being bent at right angles, as indicated at 115. A plate 116 is secured by screws 117 to the bent portion 115 of the lifting member, said plate being provided with lifting shoes 118 which stand normally beneath and out of contact with the feed rack 18 but are adapted to be 115 swung upwardly to engage with and lift said feed rack, one of said lifting shoes being at either side of the feed pinion 21.

As best appears from an inspection of Fig. 4, each push rod 68 passes through a bearing opening in the release plate 98, which plate serves as a forward bearing for the set of push rods. Around each bearing opening in the plate 98 are grouped a set of four perforations or holes, numbered 119, 120, 121 and 122, which holes are adapted to co-operate respectively with the limiting pins 91, 92, 93 and 94 on the associate tabulating key 81. A denomination scale 123 of ordinary construction is suitably secured to the front of 130

the base of the machine and is provided above each of the keys 81 with a denomination mark corresponding with said key. One of the ordinary systems of notation is employed to mark the scale shown in the drawings, which reads from left to right:—

1 10 100 1000 10T 100T 1M

It will be understood that the number of column stops employed will depend upon the character of the tabulating work in hand and that while four column stops are shown in the drawings, a less or greater number may be employed, care being taken to arrange them consecutively from left to right upon the rack bar 33.

Let it be assumed that the operator is engaged in making up a tabular statement, that in such statement there are to be four columns running up and down the sheet in about the relative positions indicated by the column stops 38, 39, 40 and 41 in Fig. 1, and that a line has been partly written so that the carriage has moved about thirty-five spaces from left to right, and is in approximately the position shown in Fig. 1. If then, it be desired to write a certain amount, say \$2000, in the third column, the operator presses his finger in the depression 89 (which depression bears the numeral "3", indicating the third columnar position) in the fifth tabulating key 81 counting from the left, which key, as indicated by the denominational scale 123 is the "thousands" key. As the finger is pressed against the depression 89, the key 81 turns on the spherical bearing 80, and the limiting pin 93, behind said depression 89, is thereby guided between the two lowermost arms 97 of the positioning member 95, said pin being finally brought to a stop in the crotch formed by the meeting of said lower arms 97. Further motion of the key on its bearing 80 now being prevented, continued pressure against the depression 89 will cause a rearward longitudinal movement of the push rod 68, and this rearward movement will continue without obstruction until the rear end of the limiting pin 93 contacts with the face of the release plate 98. The limiting pin 94 is longer than the pin 93 and consequently reaches the plane of the release plate before the pin 93 does, but said pin 94 enters its associate hole 122 and does not contact with said plate. As the fifth rod 68 is pushed rearwardly its cam face 78 first engages the associate pin 60 depending from the bar 59 and the action of the cam on the pin swings the lower arm of the lever 56 leftward on the pivot 47, and the upper arm of said lever 60 rightward on said pivot 47 until the end of the cam is reached and the pin 60 engages with the retaining recess 79, thereby preventing further lateral movement of the denomination stop member. The cam is so proportioned that when the end of it is

reached the lug 52^b will be opposite the space between the fifth and sixth teeth in the guide comb 54. Thereafter, as the rod 68 continues to be pushed rearwardly it acts on the pin 62 to swing the lower arm of the lever 52 rearwardly about the fulcrum 51 and the upper arm of said lever forwardly about said fulcrum 51, causing the lug 52^b to enter the space between the fifth and sixth teeth in the guide comb 54 and moving the contact or stop portion 52^a of the lever 52 forwardly into the path of the column stops. During this forward movement or projection of the stop portion 52^a the pin 92 contacts with the release plate 98 as heretofore described, so that further pressure on the tabulating key will slide the plate 98 rearwardly in its bearings and will thereby cause the rack lifting member 113, through the train of mechanism comprising the rod 102, bell crank 105 and link 111, to be swung upwardly until the shoes 118 engage the feed rack 18 and swing it upward about its pivot 20 so as to disengage said rack from the pinion 21. As soon as this disengagement occurs the carriage is free to be "jumped" or drawn rapidly leftward across the machine under the influence of the spring drum 31. The parts are so proportioned and arranged that when the release occurs the contact portion 52^a of the denomination stop member has been projected far enough forward to engage the third column stop 40, but not far enough forward to engage either of the column stops 38 or 39, which will both pass or skip the denomination stop member. Consequently the carriage will move freely leftward until the third column stop 40 contacts with the engaging portion 52^a of the denomination stop member. This member, it will be understood, has previously been rotated rightward on the fulcrum or pivot 47 until it is in the fifth denomination position, so that when the carriage is arrested the printing point on the platen will correspond with the "thousands" position in the third column of the work.

When the tabulating key is released the first part of its return motion permits the carriage feed rack 18 to drop into engagement with the pinion 21 under the influence of the feed rack spring (not shown). The contact portion 52^a of the stop member will be swung rearwardly about the pivot 51 under the influence of the spring member 61, and as soon as the lug 52^b disengages from the guide comb the coiled spring 66 serves to swing the denomination stop member about the fulcrum 47 until the right-hand end of the stop bar 59 contacts with the limiting stop 67, and the restoring spring 71 serves to restore the push rod 68 to normal position. The releasing devices comprising the release bar and the parts normally connected therewith, are restored to normal

95

105

110

115

120

125

130

position under the influence of gravity. The number desired, *i. e.*, 2000, may then be written in the third column by actuating the printing devices in the usual manner, 5 after which the above outlined operation may be repeated with any key to cause the set of stops comprising the denomination stops and the plurality of column stops, to coöperate as desired.

10 It will be understood that by means of the member 76 the denomination stop member may be swung variable distances about the fulcrum 47 from side to side of the machine, this swinging movement or lateral throw depending upon which of the tabulating keys is operated and the fulcrum 47 acting as a rock shaft and rocking to different extents for each member 76. It will clearly be perceived from a consideration of Fig. 1 that the 15 extreme right-hand tabulating key, *i. e.*, the "millions" key actuates the member 76 which is provided with the broadest cam face 78 so that said right-hand cam member will swing the denomination stop member a greater distance than any other cam member, and that the succeeding keys are 20 adapted to swing said member through distances progressively less. The extreme left-hand tabulating key, it will be observed, actuates that member 76 which lacks a cam face, so that the left-hand member 76 does not act to swing the denomination stop member laterally at all, but only to throw said member forwardly to engage between the first and second teeth of the guide comb 25 54. It will further be understood that after the denomination stop member has been positioned laterally or sidewise, it is swung or rotated forwardly about the fulcrum, 51 into position to coöperate with a previously selected column stop, and that the means for varying the forward swing of said denomination stop is provided by the keys 81. It will be understood that the limiting pins 45 of each key vary in length, increasing progressively from the one behind the depression 87 or finger hole marked "1" to that marked "4", and that that limiting pin, whose corresponding depression or finger hole is pressed by the operator, will contact with the release plate 98, the other three pins being so positioned with respect to their respective holes that they will register with said holes, while the other pin will contact 50 between its hole and the bearing hole of the rod 68 with the face of said release plate. By this device, the time during the rearward movement of the rod 68 at which the release plate will be actuated to lift the carriage 60 feed rack and release the carriage is varied; and it will be understood that the parts are so proportioned and arranged that the release of the carriage occurs at the time that the variably movable denomination stop has been projected forwardly into the field of the 55

selected column stop. This releasing of the carriage is brought about by the tabulating keys at the last part of their rearward movement and after they have previously been moved in a rotary direction on the ball 80, 70 the extent of rearward movement of the key to release depending on the direction of the prior rotary movement thereof. The swivel joint of the positioning denomination stop member enables it to be variably positioned 75 or rotated in two directions both laterally of the machine in the direction of the carriage run or travel and fore and aft of the machine to and away from the column stops, and the key actuated means above described affords 80 a ready and comparatively simple method of positioning said denomination stop member at one operation to bring the printing point on the platen to any desired denomination position in any desired column field, 85 notwithstanding the fact that one or more column stops may intervene between the denomination stop and the column stop belonging to the desired column field.

Where in the claims I use the term "variably projecting column stops" I mean this term to be understood in a broad sense to cover any variation of said column stops, whereby the coöperation of the denomination stop with the column stops is rendered 90 selective in its character; and I do not mean my claims to be restricted to column stops projecting to different extents from their support, except in those claims where such limitation is definitely expressed. 100

Various changes in the construction of the parts and arrangements of the combinations may be made and parts of the invention may be used without other parts, all without departing from the spirit and scope of the invention. 105

What I claim as new and desire to secure by Letters Patent, is:—

1. In a typewriting machine and tabulating mechanism, the combination with a carriage, of a series of column stops, a single co-operating stop, and means for automatically releasing said carriage and for effecting variable relative adjustments between said stops to select denominational positions and for effecting other variable relative adjustments to select columns to bring said stops into co-operation to arrest the carriage at any desired denominational position within any desired columnar field by a single operation. 110 115

2. In a typewriting machine and tabulating mechanism, the combination of a carriage, a series of column stops, a single stop co-operating therewith, a series of keys, means operated by said keys for effecting 120 variable relative adjustments between said stops to select denominational positions and for effecting other variable relative adjustments to select columns to bring the stops into co-operation to arrest the carriage at any 125 130

desired denominational position within any desired column without first arresting the carriage at a preceding column, and means operated by said keys for releasing the carriage.

3. In a typewriting machine and tabulating mechanism, the combination of a carriage, a series of column stops, a single stop coöperating therewith, and key actuated means for effecting a relative adjustment of said stops in the direction of the run of the carriage to determine the denominational position of arrest of the carriage and for effecting another relative adjustment of said stops to bring said single stop and any desired column stop into coöperation, so that the carriage can be stopped at any desired denominational position in any desired columnar field without arresting the carriage at the preceding columnar fields.

4. In a typewriting machine and tabulating mechanism, the combination of a carriage, a series of column stops, a single stop coöperating therewith, key actuated means for effecting a relative adjustment of said stops in the direction of the run of the carriage to determine the denominational position of arrest of the carriage and for effecting another relative adjustment of said stops to bring said single stop and any desired column stop into coöperation, so that the carriage can be stopped at any desired denominational position in any desired columnar field without arresting the carriage at the preceding columnar fields, and means controlled by said key actuated means for automatically releasing the carriage.

5. In a typewriting machine and tabulating mechanism, the combination of a carriage, column stops therefor, and a stop that is moved in the direction of the travel of the carriage to different extents to determine the denominational position of arrest and which is moved to different extents at substantially right angles to the travel of the carriage to determine the columnar position of arrest.

6. In a typewriting machine and tabulating mechanism, the combination of a carriage, column stops therefor, a stop that is moved in the direction of the travel of the carriage to different extents to determine the denominational position of arrest and which is moved to different extents at substantially right angles to the travel of the carriage to determine the columnar position of arrest, and means for automatically releasing the carriage.

7. In a typewriting machine and tabulating mechanism, the combination of a carriage, column stops therefor, a stop that is moved in the direction of the travel of the carriage to different extents to determine the denominational position of arrest and which is moved to different extents at substan-

tially right angles to the travel of the carriage to determine the columnar position of arrest, means for automatically releasing the carriage, and a key for effecting an operation of said stop in the two directions specified 70 and for operating said carriage releasing means.

8. In a typewriting machine and tabulating mechanism, the combination of a carriage, a stop that is movable to different extents in each of two directions, the movement in one direction determining the denominational position of arrest of the carriage, and the other the columnar position of arrest, and means coöperating with said stop 75 to effect an arrest of the carriage in a selected columnar position and in a selected denominational position within the column.

9. In a typewriting machine and tabulating mechanism, the combination of a carriage, a stop that is movable to different extents in each of two directions, the movement in one direction determining the denominational position of arrest of the carriage, and the movement in the other direction determining the columnar position of arrest, means coöperating with said stop to effect an arrest of the carriage in a selected columnar position and in a selected denominational position within the column, and 90 means for automatically releasing the carriage.

10. In a typewriting machine and tabulating mechanism, the combination of a carriage, a series of stops, a single coöperating 100 stop, and means for effecting relative movements to different extents and in each of two directions between said stops, the relative movement between the stops in one direction determining the denominational position of arrest of the carriage, and the relative movement between the stops in the other direction determining the columnar position of arrest of the carriage.

11. In a typewriting machine and tabulating mechanism, the combination of a carriage, a series of stops, a single coöperating 110 stop, means for effecting relative movements to different extents and in each of two directions between said stops, the relative movement between the stops in one direction determining the denominational position of arrest of the carriage and the relative movement between the stops in the other direction, determining the columnar position of arrest 115 of the carriage, and means for automatically releasing the carriage when said stops are brought into coöperative relation.

12. In a typewriting machine and tabulating mechanism, the combination of a carriage, a series of stops, a single coöperating 125 stop, and key-controlled means for effecting relative movements to different extents and in each of two directions between said stops, the relative movement between the stops in 130

one direction determining the denominational position of arrest of the carriage and the relative movement between the stops in the other direction determining the columnar 5 position of arrest of the carriage.

13. In a typewriting machine and tabulating mechanism, the combination of a carriage, a series of stops, a single coöperating stop, and key-controlled means for effecting 10 relative movements to different extents and in each of two directions between said stops, the relative movement between the stops in one direction determining the denominational position of arrest of the carriage and 15 the relative movement between the stops in the other direction determining the columnar position of arrest of the carriage, said means also operating to release the carriage when said stops are brought into coöperative relation. 20

14. In a typewriting machine and tabulating mechanism, the combination of a carriage; a plurality of stops; and key actuated means for moving one of said stops relatively 25 to the others in different directions and to different extents in each direction of movement.

15. In a typewriting machine and tabulating mechanism, the combination of a carriage; a plurality of stops; and key actuated 30 means for moving one of said stops relatively to the others in different directions and to different extents in each direction, the relative movement of the stops in one direction determining the denominational position and 35 the relative movement in another direction determining the columnar position of the carriage.

16. In a typewriting machine and tabulating mechanism, the combination of a carriage; a plurality of stops; key actuated 40 means for moving one of said stops relatively to the others in different directions and to different extents in each direction of movement, and means for automatically releasing 45 the carriage.

17. In a typewriting machine and tabulating mechanism, the combination of a carriage, tabulating stops, means for effecting a relative rotation to different extents between 50 said stops to arrest the carriage at any desired columnar field without first arresting said carriage at a preceding columnar field, and means for effecting a distinctive relative movement to different extents between said 55 stops to arrest the carriage in different denominational positions.

18. In a typewriting machine and tabulating mechanism, the combination of a carriage, tabulating stops, means for effecting a 60 relative rocking motion to different extents between said stops to arrest the carriage at any desired columnar field without first arresting said carriage at a preceding columnar field, means for effecting a distinctive relative movement to different extents between 65

said stops to arrest the carriage in different denominational positions, and means for automatically releasing the carriage.

19. In a typewriting machine and tabulating mechanism, the combination of a carriage, tabulating stops, hand actuated means 70 for effecting a relative movement between said stops to different extents in each of two directions to arrest the carriage in any desired columnar position and in any desired 75 denominational position within the selected columnar field, and means for automatically releasing the carriage at the same instant relative to the time the stops are brought into coöperative relation irrespective of the 80 extent of movement transmitted thereto.

20. In a typewriting machine and tabulating mechanism, the combination of a carriage, a series of column stops that extend 85 different distances from their support, a coöperating stop, means for effecting relative movements of the stops towards and away from each other to different distances, and means for effecting relative movements to different extents between the stops in the direction of the travel of the carriage, and means for releasing the carriage.

21. In a typewriting machine and tabulating mechanism, the combination of a carriage, a stop bar, a series of adjustable column stops carried thereby and projecting to different distances therefrom, a coöperating denominational stop, means for moving said denominational stop to different distances to coöperate with the different column stops, and means for effecting relative denominational movements of said stops to arrest the carriage in any desired denominational position within the selected columnar field. 105

22. In a typewriting machine and tabulating mechanism, the combination of a carriage, a stop bar, a series of column stops carried by said stop bar and projecting different distances therefrom, a single stop coöperating with the column stops, and means coöperating with said single stop to move it different extents in each of two directions, one direction being transverse to the direction of the travel of the carriage, to bring said single 110 stop into coöperation with the column stop it is desired to select, so as to afford an arrest of the carriage in any desired columnar field without first arresting the carriage at a preceding columnar field, and the other movement of said single stop being in the direction of the travel of the carriage to determine 115 the denominational position of arrest within the selected columnar field. 120

23. In a typewriting machine and tabulating mechanism, the combination of a carriage, a stop bar, a series of column stops carried by said stop bar and projecting different distances therefrom, a single stop coöperating 125 with the column stops, and key actuated 130

means coöperating with said single stop to move it different extents in each of two directions, one direction being transverse to the direction of the travel of the carriage to bring said single stop into coöperation with the column stop it is desired to select, so as to afford an arrest of the carriage in any desired columnar field without first arresting the carriage at a preceding columnar field, and the other movement of said single stop being in the direction of the travel of the carriage to determine the denominational position of arrest within the selected columnar field, the same key-actuated means effecting both movements of the said single stop.

24. In a typewriting machine and tabulating mechanism, the combination of a carriage, a stop bar, a series of column stops carried by said stop bar and projecting different distances therefrom, a single stop coöperating with the column stops, means coöperating with said single stop to move it different extents in each of two directions, one direction being transverse to the direction of the travel of the carriage to bring said single stop into coöperation with the column stop it is desired to select, so as to afford an arrest of the carriage in any desired columnar field without first arresting the carriage at a preceding columnar field, and the other movement of said single stop being in the direction of the travel of the carriage to determine the denominational position of arrest within the selected columnar field, and means for automatically releasing the carriage after the stops have been brought into coöperative relation.

25. In a typewriting machine and tabulating mechanism, the combination of a carriage, a stop bar, a series of column stops carried by said stop bar and projecting different distances therefrom, a single stop coöperating with the column stops, key actuated means coöperating with said single stop to move it different extents in each of two directions, one direction being transverse to the direction of the travel of the carriage to bring said single stop into coöperation with the column stop it is desired to select, so as to afford an arrest of the carriage in any desired columnar field without first arresting the carriage at a preceding columnar field, and the other movement of said single stop being in the direction of the travel of the carriage to determine the denominational position of arrest within the selected columnar field, the same key actuated means effecting both movements of the said single stop, and carriage releasing means controlled by said key actuated means.

26. In a typewriting machine and tabulating mechanism, the combination of a carriage; tabulating stops; a key-carrying part; a key that controls the relation of said stops.

65 said key being mounted on and movable independently of said key-carrying part; and a carriage releasing frame through which said key-carrying part projects and which is moved by said key and affords an independent movement of said key-carrying part. 70

27. In a typewriting machine and tabulating mechanism, the combination of a carriage, a stop bar, a series of adjustable column stops carried by said bar and projecting different extents therefrom, a coöperating 75 denomination stop mounted by a swivel joint and movable in two directions, and a series of key actuated members having cam faces, said members operative on said denomination stop to move it in two directions 80 to cause it to coöperate with any desired one of said column stops so as to arrest the carriage in any selected denominational position in any selected column.

28. In a typewriting machine and tabulating mechanism, the combination of a carriage, a stop bar, a series of adjustable column stops carried by said bar and projecting different extents therefrom, a coöperating denomination stop mounted by a swivel joint 90 and movable in two directions, a series of key actuated members having cam faces, said members operative on said denomination stop to move it in two directions to cause it to coöperate with any desired one of 95 said column stops so as to arrest the carriage in any selected denominational position in any selected column, and a carriage releasing mechanism automatically operated when any of said cam members is operated. 100

29. In a typewriting machine and tabulating mechanism, the combination of a carriage; a carriage releasing mechanism; a stop bar; a series of adjustable column stops carried by said bar and projecting to different 105 extents therefrom; a coöperating denomination stop mounted by a swivel joint and movable in two directions; a series of push rods; a series of differential members having cam faces mounted on the ends of said push rods and operative on said denomination stop; and keys on the other end of said push rods; each of said keys being independently movable in different directions for the purpose of properly timing the carriage releasing 110 mechanism, said keys having portions operative on said releasing mechanism. 115

30. In a typewriting machine and tabulating mechanism, the combination of a carriage, a series of stops, and key actuated means for moving certain of said stops relatively to others in different directions and to different extents in each direction of movement.

31. In a typewriting machine and tabulating mechanism, the combination of a carriage, a series of stops, and key actuated means for moving certain of said stops rela-

tively to others to different extents in each of a plurality of different directions, the relative movements between the stops in one direction determining the denominational 5 position of arrest of the carriage and the relative movement between the stops in another direction determining the columnar position of arrest.

32. In a typewriting machine and tabulating mechanism, the combination of a carriage, a series of stops, key actuated means for moving certain of said stops relatively to others in different directions and to different extents in each direction of movement, and 10 means for automatically releasing the carriage.

33. In a typewriting machine and tabulating mechanism, the combination of a carriage, a series of stops, and key actuated 20 means for moving certain of said stops relatively to others in different directions and to different extents in each direction of movement and for automatically releasing the carriage, a single key stroke effecting the 25 proper relative positioning of the stops and the release of the carriage.

34. In a typewriting machine and tabulating mechanism, the combination of a carriage, a series of stops, and key actuated 30 means for moving certain of said stops relatively to others in different directions and to different extents in each direction of movement, a single operation of a key effecting the 35 relative movements of the stops in two directions and to the desired extents.

35. In a typewriting machine and tabulating mechanism, the combination with a carriage, of variably projecting column stops, a single coöperating stop having a variable 40 movement in each of two directions, and means for moving said coöperating stop different extents in each direction to arrest the carriage in any desired denominational 45 position within any desired columnar field by a single operation.

36. In a typewriting machine and tabulating mechanism, the combination with a carriage, of variably projecting column stops, a single coöperating stop having a variable 50 movement in each of two directions, and means for automatically releasing said carriage and moving said coöperating stop different extents in each direction to arrest the carriage at any desired denominational 55 position within any desired columnar field by a single operation.

37. In a typewriting machine and tabulating mechanism, the combination of a carriage, a series of variably projecting column 60 stops, a single stop coöperating therewith, said single stop and said series of column stops having a variable relative movement; a key; means controlled by said key for effecting different extents of relative motion

between said single stop and said series of column stops to arrest the carriage at any desired columnar field without first arresting the carriage at a preceding columnar field; and means for variably arresting said key.

38. In a typewriting machine and tabulating mechanism, the combination of a carriage, a series of variably projecting column stops, a single stop coöperating therewith, said single stop and said series of column stops having a variable relative movement, a 75 key; means controlled by said key for effecting different extents of relative motion between said single stop and said series of column stops to arrest the carriage at any desired columnar field without first arresting the carriage at a preceding columnar field; and means for variably arresting said key, said means being operated by said key to automatically release the carriage.

39. In a typewriting machine and tabulating mechanism, the combination of a carriage, a series of variably projecting column stops, a single stop coöperating therewith and having a variable movement in each of two directions, a series of keys, and means 85 operated by said keys for moving said coöperating stop different extents in each direction to arrest the carriage at any desired denominational position within any desired column without first arresting the carriage 95 at a preceding column.

40. In a typewriting machine and tabulating mechanism, the combination of a carriage, a series of variably projecting column stops, a single stop coöperating therewith 100 and having a variable movement in each of two directions, a series of keys, and means operated by said keys for automatically releasing the carriage and moving said coöperating stop different extents in each direction to arrest the carriage at any desired 105 denominational position within any desired column without first arresting the carriage at a preceding column.

41. In a typewriting machine and tabulating mechanism, the combination of a carriage, a series of variably projecting column stops, a single coöperating stop, said coöperating stop and said series of column stops having a variable relative movement in the 110 direction of the run of the carriage to determine the denominational position of arrest of the carriage and having a variable relative movement in another direction to determine the columnar position of arrest, and key- 115 actuated means for imparting such relative movements to the stops.

42. In a typewriting machine and tabulating mechanism, the combination of a carriage, a series of variably projecting column 120 stops, a single coöperating stop, said coöperating stop and said series of column stops having relative movement in two directions

and to different extents in each direction, and key-controlled means for controlling the extent of relative movement of said stops in both directions to arrest the carriage at any 5 desired denominational position in any desired column.

Signed at the borough of Manhattan, city

of New York, in the county of New York, and State of New York, this 14th day of October, A. D. 1905.

MORRIS W. POOL.
